UNITED STATES PATENT OFFICE

102,755

DESIGN FOR A COMBINED PERPETUAL CALENDAR AND HOLDER THEREFOR

Gerhard Martin Lee, Aurora, Ill., assignor to
W. H. McCullouch, doing business as Finch &
McCullouch, Aurora, Ill.

Application October 29, 1936, Serial No. 65,586

Term of patent 14 years

To all whom it may concern:

Be it known that I, Gerhard Martin Lee, a citizen of the United States, residing at Aurora, county of Kane, and State of Illinois, have invented a new, original, and ornamental Design for a Combined Perpetual Calendar and Holder Therefor, of which the following is a specification, reference being had to the accompanying drawing, forming a part thereof, in which:

The figure is a perspective view of a combined perpetual calendar and holder therefor embodying the invention.

I claim:

The ornamental design for a combined perpetual calendar and holder therefor, as shown.

GERHARD MARTIN LEE.
